US00D986071S

(12) **United States Design Patent** (10) Patent No.: **US D986,071 S**
(45) Date of Patent: **** May 16, 2023**

(54) **2-ZONE WIRELESS CONTROL WATER TIMER**

(71) Applicant: **FUJIAN BALDR TECHNOLOGY CO., LTD.**, Fujian (CN)

(72) Inventor: **Zhong Dong Huang**, Fujian (CN)

(73) Assignee: **Fujian Baldr Technology Co., Ltd.**, Fuzhou (CN)

(**) Term: **15 Years**

(21) Appl. No.: **29/779,167**

(22) Filed: **Apr. 16, 2021**

(51) LOC (14) Cl. **10-03**

(52) U.S. Cl.

USPC **D10/40**

(57) **CLAIM**

The ornamental design for a 2-zone wireless control water timer, as shown and described.

DESCRIPTION

FIG. 1 is a perspective view of a 2-zone wireless control water timer showing my new design;

FIG. 2 is a front view thereof;

FIG. 3 is a left side view thereof;

FIG. 4 is a right side view thereof;

FIG. 5 is a back view thereof;

FIG. 6 is a top view thereof; and,

FIG. 7 is a bottom view thereof.

The broken lines illustrate portions of the 2-zone wireless control water timer that form no part of the claimed design.
